UNITED STATES PATENT OFFICE.

NATHAN RAPPOR^T, OF NEW YORK, N. Y.

DESIGN FOR A COMBINED CHECKER AND CHESS BOARD.

Application filed July 18, 1927. Serial No. 22,803. Term of patent 3½ years.

To all whom it may concern:

Be it known that I, NATHAN RAPPOR^T, a citizen of the United States, residing in New York, county of Bronx, and State of New York, have invented a new, original, and ornamental Design for Combined Checker and Chess Board, of which the following is a specification, reference being had to the accompanying drawing, forming part thereof, in which—

Figure 1 is a plan view, and
Figure 2 is an edge view of my combined checker and chess board.

I claim:

The ornamental design for a combined checker and chess board, as shown.

NATHAN RAPPOR^T. [L. S.]
